UNITED STATES PATENT OFFICE.

MAGGIE GOLDSMITH, OF SAN FRANCISCO, CALIFORNIA.

CURTAIN OR DRAPERY PROTECTOR.

SPECIFICATION forming part of Letters Patent No. 761,293, dated May 31, 1904.

Application filed September 16, 1903. Serial No. 173,423. (No model.)

To all whom it may concern:

Be it known that I, MAGGIE GOLDSMITH, a citizen of the United States, residing in the city and county of San Francisco and State 5 of California, have invented new and useful Improvements in Curtain and Drapery Protectors, of which the following is a specification.

My invention relates to an improved device 10 for gathering up and protecting curtains or draperies when the room in which they are hung is to remain unused for any considerable length of time or when it is desired to sweep the room.

15 It consists of the parts and the construction and combination of parts, having reference to the accompanying drawings, in which—

Figure 1 shows the application of my device. Fig. 2 shows the bag when in elevated 20 position.

A represents a bag having an open mouth and supported by the cords 2 2', which pass over pulleys 3 3' at the top of the window-frame.

25 Pulley 3 is preferably double and both cords pass through it, cord 2 running directly down to connect with one end of the rectangular wire frame 4, to which the open end of the bag is attached and by which the end is 30 always kept distended. Cord 2' is supported intermediate of the pulleys by means of the rings 5, attached to a flexible tape 6, and from pulley 3' passes down and connects with the opposite end of frame 4.

35 By employing a tape, as 6, and sewing or otherwise suitably attaching rings to it I provide a convenient cord-support, which may be made in any length originally and be cut off subsequently to fit any width of window, the 40 tape being quickly secured to the woodwork by means of a few tacks. The bag is of a width corresponding with that of the window-opening, and the cords are adapted to be operated in unison, so as to raise or lower the

45 bag to allow the curtains or draperies which usually grace the window to fold naturally into the bag. The curtains are gathered up within the bag as the latter is raised, and the mouth of the bag is adapted to close over the

upper end of the curtains and prevent any ingress of dust. Any suitable means may be employed to cause this final closing of the bag. I have shown stops 7, rigid on the window-frame, disposed in the path of the bag-frame 4 below and adjacent to pulleys 3 3', whereby the inner side of the frame is engaged as the bag is drawn up, causing the open end of the bag to turn outward from a horizontal plane and to lie approximately parallel with and against the wall-surface, in which position little, if any, dirt can get into the bag. The bag is held with the enfolded curtains in elevated position by engaging the connected ends of the cords over a hook, as 10, or other suitable fastening device. The bag is provided with a central diagonal slit 9, through which the operator's hand may pass to straighten out the folds of the curtain in the bottom of the bag as the latter is raised and so prevent the curtains being rumpled 70 unnecessarily.

By disposing the slit diagonally, as shown, all liability of the curtains catching on the edges of the opening and protruding is obviated, since the pocket is self-closing.

When the sweeping is done, or when the room is once more opened up for occupancy, the bag is lowered and detached by any well-known method, or the entire device may be removed from the window-frame by removing the tape and lifting the cords from the pulleys, and the curtains shaken out, having been completely protected from the dust and the usual rough handling incident on house-cleaning.

I do not limit my invention to a bag of any particular shape and size, as the dimensions of the bag and its shape will often depend upon the shape of the window or the arrangement of the curtain or drapery.

Having thus described my invention, what I claim, and desire to secure by Letters Patent, is—

1. The combination with a curtain or drapery, of a receiver including a receptacle closed at the bottom, ends, and sides and open at the top, and pull-cords connected to the receptacle whereby said receptacle is movable

in the vertical plane of the drapery to progressively inclose, or uncover, the same as it is moved in relation thereto.

2. The combination with a vertically-pend-
5 ent curtain or drapery, of a bag-like structure with closed sides, bottom and ends and unattached to the drapery, and means whereby the said structure is movable vertically to progressively inclose, or uncover, the drapery as
10 it is moved in relation thereto.

3. The combination with a curtain or drapery, of a protector therefor comprising an open-mouth bag pendent in the line of the curtain or drapery and means for raising and
15 lowering the bag.

4. The combination with a curtain or drapery, of a protector therefor comprising an open-mouth bag pendent in the line of the curtain or drapery and means for raising and
20 lowering the bag and for holding it at any desired elevation.

5. The combination with a curtain or drapery, of a protector therefor comprising an open-mouth bag pendent in the line of the curtain or drapery means for raising and lower-
25

ing the bag, and means by which the open end of the bag is closed over the top of the curtain or drapery.

6. The combination with a curtain or drapery, of a protector therefor comprising a 30 pendent open-mouth bag, pull-cords for the same whereby the curtain or drapery is progressively inclosed by and evenly folded within the bag, and a support for said cords including a flexible tape and rings secured thereto.

7. The combination with a curtain or drapery, of a protector therefor comprising a bag disposed in the line of the curtain or drapery and means for raising and lowering the bag, 40 the latter having a diagonally-disposed slit in one side for the purpose described.

In testimony whereof I have hereunto set my hand in presence of two subscribing witnesses.

MAGGIE GOLDSMITH.
